HAIR WAVER

Leo Roitner, Kirkland Lake, Ontario, Canada
Application March 11, 1954, Serial No. 415,629

5 Claims. (Cl. 132—129)

This invention relates to the art of hair waving and more particularly to a device which is especially designed for the home user in that it may be readily applied by the person desiring the hair wave.

Prior art hair waving apparatuses used heretofore are entirely unsuitable for the purposes of this invention in that such devices either involved an unusually large number of parts and were consequently too difficult to operate or were of the pinch wave variety which merely gripped the hair tightly between two clamps producing kinks in the hair. The invention described herein provides a hair waver which is easy to operate and which produces a smooth pleasing wave.

The presently described hair waver includes a pair of toothed clamping members between which is disposed a comb. Mounted on the comb are finger grips which when pressed between the thumb and forefinger cause the clamping members to pivot outwardly and the comb to move endwise. In this extended position the comb is passed through the hair and, when the device is positioned where a wave is desired, the finger grips are released. It can be seen that the hair passing between the teeth of the clamping members and the teeth of the comb will be laterally displaced by the endwise movement of the comb and will be tightly retained in this position by the intermeshing teeth of the clamping member. A group of strands of hair is thereby individually waved by being held between pairs of teeth on the clamping members and a pair of teeth in the comb. In this manner a smooth pleasing wave is produced which has no kinks or unsightly sharp corners.

An object of the present invention is to provide a hair waving device which produces a lasting smooth wave and which is readily usable by the individual desiring the hair wave.

Another object of the present invention is to provide a hair waving device which is constructed of relatively few parts and which is easy to assemble and disassemble.

Still another object of the present invention is to provide a hair waving device in which a comb is disposed between two clamping members and in which the comb is adapted for endwise movement upon opening movement of the clamping members.

Other objects and many of the attendant advantages of the present invention will become apparent in the light of this specification when considered in connection with the accompanying drawing wherein:

Fig. 1 is a perspective view of the hair waver in the closed position;

Fig. 2 is a perspective view of the hair waver in the open or extended position;

Figs. 3, 4 and 5 are respectively plan, front and end views of one of the clamping members;

Figs. 6, 7 and 8 are respectively plan, front and end views of the other clamping member;

Figs. 9 and 10 are front and end views of the comb;

2

Figs. 11 and 12 are front and end views of the finger grip;

Figs. 13 and 14 are front and end views of the sleeve employed with the present invention;

Fig. 15 is a cross-sectional view along the line 2—2 of Fig. 1; and

Fig. 16 is a cross-sectional view along the line 3—3 of Fig. 2.

There is provided a pair of clamping or hair gripping members 21 and 22 which have teeth 23 and 24 inwardly bent at the lower ends thereof as clearly shown in Figs. 5 and 8 so that these teeth will intermesh when the hair waver is in the closed position shown in Fig. 1. Member 21 is provided with outwardly curved end portions 25 and inwardly bent flanges 26 and 27 as seen in Fig. 3 which project inwardly from the upper edges of the clamping member a distance corresponding to the distance the teeth project inwardly. Flange 26 is provided with a slot 28 disposed in the manner shown in Fig. 5 for a purpose to be explained more fully hereinafter. Flange 27 is provided with a circular aperture 29 which is of the same diameter as the length of slot 28 and which is shown in dotted lines, Fig. 5. Clamping member 22 is similarly provided with inwardly extending flanges 31 and 32, flange 31 being provided with circular aperture 33 and flange 32 being provided with slot 34.

There is disposed between the clamping members a comb 35 the details of which are clearly shown in Figs. 9 and 10. The lower portion of the comb 35 is provided with laterally curved teeth 36 and integral with comb 35 is a neck portion 37 connecting with an elongated rectangular shaped element or bar 38 and a finger grip 39. The ends of bar 38 are twisted in the same direction as shown at 41 and 42 so that the ends of the bar are offset approximately 30° with respect to the center portion of the bar thus forming cam surfaces. It can be seen that the comb may be formed from a single piece of malleable metal, metal being cut away to form the teeth and elongated bar 38 and the finger grip being formed by twisting the metallic tab 90°.

Figs. 11 and 12 illustrate the other finger gripping element utilized with the present invention. Member 43 is of a U-shaped configuration having an upwardly extending finger gripping portion 44 and a slot 45 formed in the bend of the U. Both arms of the U are provided with apertures 46 of a diameter the same as apertures 29 and 33.

The hair waving apparatus disclosed herein is assembled in the following manner. The clamping members 21 and 22 are placed in juxtaposition with their flanges adjacent and flange 31 of member 22 is placed within the U of member 43. The comb is then brought into position passing end 42 of bar 38 through the apertures in the U-shaped member 43, flange 31 and the slot in flange 26. The opposite end 41 of member 38 is passed through the aperture and slot in flanges 27 and 32 respectively. There is provided as shown in Figs. 13 and 14 a sleeve 47 which is formed from a rectangular metallic strip having the ends thereof cut in the form of an interengaging V-shape as shown at 48. This sleeve is opened and fitted between finger grip 39 of comb 35 and flange 27 of clamping member 21. Spring 49 encircles bar 38 and engages neck portion 37 of comb 35 and flange 26 of clamping member 21.

The operation of the hair waving device herein disclosed is as follows. In the closed position shown in Fig. 1 the teeth of the comb are in substantial alignment with the teeth of clamping member 22 and the lower ends of the inwardly bent teeth of the clamping members are intermeshing. Finger grips 39 and 44 are grasped between the thumb and forefinger and pressed to compress spring 49. This action causes the

comb and clamping members to move relative to one another endwise to positions laterally displaced from their normal positions with the comb disposed between the clamping members and also causes the clamping members to swing outwardly due to the movement of the curved ends 41 and 42 of bar 38 through slots 28 and 34 in the flanges of clamping members 21 and 22, respectively. It can be seen that the twisted ends of the bar 38 serve as cams and slots 28 and 34 of the clamping members act as cam followers. The open position is shown in Fig. 2 and in this position the device is passed through the hair to the desired position for a wave. Strands of hair will be positioned between the teeth of the clamping members and the teeth of the comb and upon release of the finger gripping elements 15 spring 49 returns the device to the closed position. It can be seen that the movement of the comb from the position of Fig. 2 will cause corresponding movement of the hair held between the teeth of the comb and thus the hair held between the clamping members will be 20 formed in a wave. The intermeshing of the teeth of the clamping members effectively prevents slipping of the device and the production of a smooth lasting wave is assured.

Having thus described the invention it is apparent that numerous changes in design and construction of the same may be employed without departing from the essentials thereof. What is claimed as new and desired to be secured by Letters Patent is:

1. A hair waving device comprising, in combination, a pair of hair gripping members, a comb member, cam means mounted on one of said members, and cooperating follower means mounted on the other member whereby upon operation of the device the hair gripping members pivot outwardly and the comb and hair gripping members move laterally with respect to one another.

2. In a hair waving device of the character described, a pair of toothed, clamping members having the ends of the teeth thereof bent, means interconnecting said toothed members whereby the teeth of said clamping members normally intermesh, a comb normally disposed between said clamping members and having the teeth thereof

substantially in alignment with the teeth of one of said clamping members, and means including said last-named means for pivoting said clamping members to an open position and for moving said comb and clamping members relative to one another endwise to positions laterally displaced from the normal positions thereof.

3. In a device of the class described, a comb having a bar connected thereto and extending longitudinally therewith, said bar having twisted ends, a pair of toothed clamping members, one of said members disposed on each side of said comb, and means mounted on said clamping members and engaging said bar whereby upon longitudinal movement of said comb the last-mentioned means and the twisted ends of said bar combine to cause the clamping members to be swung outwardly to an open position.

4. A hair waving device of the character described, a comb having mounted thereon an elongated rectangular shaped element, said element having both ends thereof twisted, a pair of clamping members having inwardly bent flanges, said flanges being provided with slots for the reception of said elongated element, one clamping member being disposed on each side of said comb, means mounted on said comb for moving said comb endwise to a position laterally displaced from the normal position thereof, the movement of the twisted ends of said elongated element through the slots in the flanges of said clamping members causing the clamping members to be pivoted to an open position.

5. A hair waving device as recited in claim 4 wherein said clamping members have teeth inwardly bent to a position wherein the lower ends of the teeth on one member are normally disposed between the lower ends of the teeth on the other member, the teeth of said comb normally being substantially in alignment with the teeth of one of said members.
